UNITED STATES PATENT OFFICE.

ALONZO E. RHOADES, OF HOPE DALE, MASSACHUSETTS, ASSIGNOR TO DRAPER CORPORATION, OF HOPE DALE, MASSACHUSETTS, A CORPORATION OF MAINE.

FEELER MECHANISM FOR LOOMS.

Application filed February 26, 1924. Serial No. 695,296.

To all whom it may concern:

Be it known that I, ALONZO E. RHOADES, a citizen of the United States, residing at Hopedale, in the county of Worcester and 5 State of Massachusetts, have invented an Improvement in Feeler Mechanisms for Looms, of which the following description, in connection with the accompanying drawings, is a specification, like characters 10 on the drawings representing like parts.

One of the objects of the present invention is to provide a feeler mechanism of the intermittent type of simple and effective construction and operation whereby the feeler 15 may be moved to an inoperative position and held during its periods of inactivity that it may not contact with the filling on detecting beats and be freed at intervals to its periods 20 of activity and call for replenishment of filling when that in the shuttle is substantially exhausted.

An important feature of the present invention consists in a feeler mechanism wherein the feeler withdrawing and holding 25 device is moved and rendered effective to perform its function by the feeler when it is moved frontwardly by a working supply of filling on a detecting beat. In accordance with this feature of the invention, the feeler 30 withdrawing and holding device is connected to the feeler in a manner such that front- 35 ward movement of the feeler by a working supply of filling on a detecting beat causes the withdrawing and holding device to be moved into cooperative relation with its ac- 40 tuating means. In one aspect of the invention, this is effected by a rack and pinion connection between the feeler and the with- 45 drawing and holding device, and a trip is employed to free the feeler at intervals that it may have periods of activity and inactivity, the former preferably being relatively short.

The invention and new combination of parts will best be made clear from the following description and the accompanying drawings of one good practical form there- 45 of, the details of which, however, may be varied within the true scope of the invention as defined by the claims.

50 In the drawings:

Fig. 1 is a perspective view of a feeler mechanism embodying the present invention and also a portion of the loom at the feeler side; and

Fig. 2 is a side elevation of the feeler 55 mechanism.

The feeler mechanism to be hereinafter described in detail provides for a change in the loom operation, such as replenishment of filling when the filling in the shuttle has become substantially exhausted, but the replenishing mechanism is not shown and described because it may be of any usual type now well understood by those familiar with weaving, and the details thereof form no es- 60 65 sential part of the present invention.

In the illustrated form of the invention, the feeler mechanism of the present invention is shown as associated with a feeler mounted for movement longitudinally of the 70 shuttle to call for a change of filling, and while the invention is well adapted for this type of feeler mechanism, the invention is not necessarily restricted thereto but may be employed with advantage in other forms 75 of feelers.

Extending from the loom frame is the usual shipper stand 1 from which projects an arm 2 to which the feeler mechanism may be adjustably secured. Supported by the 80 arm 2 is a bracket 3 which may be adjustably connected to the arm 2 by a bolt 4, as usual, and the upper portion 5 of the bracket 3 presents a convenient support for the feeler stand. 85

In the present instance of the invention the feeler stand 6 is connected to the bracket 5 in the usual manner through the slot 7, and at its rear portion has a bearing 8 provided with a guideway in which is laterally mov- 90 able a slide 9 having an opening 10 through which the feeler 11 extends. The slide 9 is connected at 12 to a transmitter 13 which may be associated with any desired type or train of mechanism for effecting replenish- 95 ment of filling when the slide 9 is moved laterally in its guides by side swipe move- 100 ment of the feeler. The slide 9 is conveniently held in its bearings or guideway by a cap plate 14 which may be secured to the rear bearing 8 by screws 15.

The frontwardly extending stem portion 16 of the feeler passes through a front guide 17 formed as a swivel block and mounted on a pin 18 for swivelling movement. Between the front bearing 17 and a collar or bridge 19 secured to the feeler is a spring 20 which normally acts upon the feeler to move 105

it to rearward feeling position, and the rear end portion of the feeler may be provided with a series of teeth 21 to engage and sink into the filling to prevent side swipe movement of the feeler during the active periods of the feeler when a working supply of filling is present in the shuttle on a detecting beat.

10 The lay 22 carries the usual shuttle box at the feeler side of the loom, and has an opening 23 which registers with a corresponding opening 24 in the shuttle 25 when the latter is in the shuttle box, so that the feeler 11, during its active period, may enter the shuttle and feel for the filling 26 which is carried on the usual filling carrier or bobbin 27.

20 The parts thus far described may be the same in construction and mode of operation as the similar parts shown and described in the patent to Edward S. Stimpson, No. 1,309,226, July 8, 1919, to which reference may be had.

25 Secured to or projecting frontwardly from the feeler stand 6 is a bracket 28, carrying a pin or dead shaft 29 for the convenient support of the devices which act upon the feeler at times to move it to and hold it in frontward inactive position, and 30 free it at times to its periods of inactivity.

35 The frontwardly extending stem 16 of the feeler is provided with a rack 30, the teeth of which mesh with the teeth of a pinion 31 loosely mounted upon the stud or dead shaft 29.

40 As shown in the present instance, the feeler withdrawing and holding member 32 is also mounted upon the stud or dead shaft 29 and is connected for rotative movement with the pinion 31 as by means of the pins 33, the construction being such that the pinion 31 and the member 32 rotate together. The member 32 is provided with a series of teeth 34, two being shown in the present instance of the invention but any convenient 45 number may obviously be employed, the construction being such that the member 32 has a toothed portion and an untoothed portion for a purpose that will presently appear.

50 Mounted upon the feeler stand for movement towards and from the front of the machine is a plunger 35, the rear end portion 36 of which is adapted to engage a surface carried by the lay on each detecting beat and 55 be moved frontwardly thereby. In the present instance, the rear end portion 36 of the plunger is shown as adjustably secured to the plunger by a nut 37 and is adapted, in the present instance, to engage the front wall of the shuttle on a detecting beat. The 60 plunger 35 is mounted in bearings of the feeler stand which may be conveniently formed by a riser 38 on the cap plate 14 to afford a rear bearing for the plunger, and the 65 laterally extending arm 39 having a bearing

portion 40 for the front end of the plunger. A spring 41 on the plunger and interposed between the front bearing 40 and the collar 42 adjustably secured to the plunger normally tends to move the plunger into its 70 rearward position, in which it may be limited by the collar 42.

Pivotedly connected to the plunger at 43 is a pawl 44, the acting end portion of which is adapted to cooperate with the teeth 75 34 of the feeler withdrawing and holding member 32 when said teeth are presented for engagement by the pawl. In the present instance, the holding pawl 45 is pivoted at 46 to the laterally extending arm 39 or a lug extending downwardly therefrom, and its active end is adapted to cooperate with the teeth 34 of the feeler withdrawing and holding member 32 to prevent retrograde movement thereof when engaged with one of said teeth.

When the feeler is moved to its rearward feeling position, as indicated in Fig. 2, the cooperative relation of the rack and pinion hereinbefore described will cause the feeler withdrawing and holding member 32 to be turned in a contra-clockwise direction, viewing Fig. 1, to carry the teeth 34 out of cooperative relation with the pawls 44 and 45, should said pawls be disengaged from 95 the cooperating teeth of the feeler withdrawing and holding member.

Loosely mounted on the stud or dead shaft 29 is a ratchet wheel 47 the teeth 48 of which are adapted to be engaged by the active end 49 of the pawl 50 pivoted at 51 to the plunger 35, and in order to prevent too loose movement of the ratchet wheel 47 friction material 52 may be caused to bear upon the disk 53 formed as shown as part of the 100 hub 54 of the ratchet wheel 47.

Mounted upon and extending laterally from the ratchet wheel is a trip or lug 55 which is of sufficient extent laterally from the ratchet wheel 47 to project beyond the active ends of the pawls 44 and 45, the construction being such that should the ratchet wheel 47 be turned clockwise, viewing Fig. 1, the trip or lug 55 will eventually rise beneath the active ends of the pawls 44 and 45 110 and lift them from engagement with the teeth 34 of the feeler withdrawing and holding member 32, whereupon the feeler, under the actuation of its spring 20, will move to rearward feeling position and thereby turn 115 the pinion 31 and the connected member 32 to carry the teeth 34 out of range of the pawls 44 and 45, thus freeing the feeler to the performance of its feeling function during 120 periods of activity.

125 Assuming that the feeler is in its rearward feeling position, as indicated in Fig. 2, the teeth 34 of the feeler withdrawing and holding member 32 will be turned out of range of the pawls 44 and 45 into the 130

position indicated in Fig. 2, at which time both pawls will operate on the untoothed portion of the member 32 and consequently be of no effect. Should the feeler meet a working supply of filling on a detecting beat when it is in active position, it will be moved forwardly through the rack and pinion connection with the feeler withdrawing and holding member 32, turning the latter to bring the teeth 34 thereof into the range of action of the pawls 44 and 45. On subsequent detecting beats the plunger 35 will engage a surface carried by the lay, as, for instance, the front wall of the shuttle, and through the active pawl 44 move the feeler withdrawing and holding member step by step in a clockwise direction, viewing Fig. 1, thereby further withdrawing the feeler through the rack and pinion connection frontwardly, so that on subsequent detecting beats the feeler will not engage the filling. As the active pawl 44 steps the feeler withdrawing and holding member 32 along, as described, the holding pawl 45 will engage one of the teeth 34 thereon and retain the feeler in its frontward position until finally the active pawl 44 will move back and forth on the untoothed portion of the feeler withdrawing and holding member 32. It will be noted that the active end of the holding pawl 45 is slightly forward of the active end of the pawl 44, so that while the pawl 44 is moving on the untoothed portion of the feeler withdrawing and holding member 32 and is consequently idle during the subsequent frontward movements of the bunter, the holding pawl will serve to hold the feeler withdrawing and holding member and, through the rack and pinion, the feeler in its frontward or inoperative position.

Since the plunger 35 is moved forwardly on the beat-up movements of the lay, the pawl 49 will step along the ratchet wheel 47 and finally carry the trip or lug 55 into position beneath the active ends of both pawls 44 and 45 and serve to disengage these pawls from the teeth 34 of the feeler withdrawing and holding member, as indicated in Fig. 2, whereupon the feeler will be freed to move to the performance of its feeling function under the call of the spring 20.

If at such times the feeler detects a working supply of filling in the shuttle, it will again be moved forwardly to bring the teeth 34 into the range of operation of the pawls 44 and 45 and the feeler will be withdrawn forwardly to its inactive position, but should the feeler detect a near approach to substantial exhaustion of filling in the shuttle, it will not be moved forwardly sufficiently far on a detecting beat to bring the teeth 34 of the feeler withdrawing and holding member into the range of action

of the pawls 44 and 45 and will consequently remain active until upon substantial exhaustion of the filling in the shuttle the feeler will call for a change of filling.

What is claimed is:

1. In a feeler mechanism for looms, the combination of a feeler having rack teeth, a pinion adapted for engagement with the rack teeth, means for turning the pinion for withdrawing and holding the feeler in a frontward inoperative position that it may not engage the filling on detecting beats during its periods of inactivity, and means for freeing the pinion at intervals during weaving with the same supply of filling that the feeler may move to feeling position. 70

2. In a feeler mechanism for looms, the combination of a feeler having a frontwardly extending stem provided with teeth, a toothed wheel engaged with the teeth of the feeler, means for turning the toothed wheel to withdraw the feeler frontwardly into an inoperative position, means for holding the toothed wheel in its feeler withdrawn position, and means for freeing the toothed wheel from its holding means at intervals that the feeler may have periods of activity and inactivity with the same supply of filling in the shuttle. 85

3. In a feeler mechanism for looms, the combination of a feeler, means for moving and holding the feeler in a frontward inoperative position including a member having a toothed and untoothed portion; a rack and pinion connection between said member and feeler, means for actuating the said member and acting through the rack and pinion to move the feeler into an inoperative frontward position, and means for freeing the said member at intervals to permit the feeler to have periods of activity and periods of inactivity. 95

4. In a feeler mechanism for looms, the combination of a feeler, a spring normally acting to move the feeler to rearward feeling position, means for moving the feeler to a frontward inoperative position and holding it for periods of inactivity, a rack and pinion connection between the feeler and said means, and a trip for freeing the feeler at intervals. 110

5. An intermittent feeler mechanism for looms, comprising in combination, a feeler, feeler withdrawing and holding means for moving the feeler to and holding it in a front position, a rack and pinion connection between the feeler and the withdrawing and holding means, and devices rendered effective to operate the withdrawing and holding means when the feeler is moved forwardly by a working supply of filling in the shuttle on a detecting beat. 120

6. An intermittent feeler mechanism for looms, comprising, in combination, a feeler, a 130

device for moving the feeler to an inoperative forward position and holding it for periods of inactivity, means for rendering the device effective to move the feeler to its 5 inoperative position by forward movement of the feeler when a working supply of filling is in the shuttle on a detecting beat, and means for tripping the device at intervals that the feeler may have periods of activity 10 and inactivity during weaving with the same supply of filling in the shuttle.

7. In an intermittent feeler mechanism for looms, the combination of a feeler, a feeler withdrawing and holding device, an 15 actuator for said device, connections between the feeler and said device for moving the latter and into control of its actuator when the feeler is moved forwardly by a working 20 supply of filling in the shuttle on a detecting beat, and means for freeing the feeler from said device at intervals that the feeler may have periods of activity and inactivity during weaving with the same supply of filling in the shuttle.

25 8. In a feeler mechanism for looms, the combination of a feeler, a feeler withdrawing and holding device, a rack and pinion connection between said device and the feeler, means for operating said device and 30 acting through the rack and pinion to withdraw and hold the feeler in an inoperative position, and means for freeing said device at intervals that the feeler may have periods of activity and inactivity during weaving 35 with the same supply of filling in the shuttle.

9. In a feeler mechanism for looms, the combination of a feeler having rack teeth, a pinion engaged therewith, a feeler withdrawing device acting through the rack and 40 pinion, a pawl for actuating said device, a pawl for holding said device in feeler withdrawn position, and a trip for freeing the device from both pawls at intervals.

10. In a feeler mechanism for looms, the 45 combination of a feeler, a rotary feeler withdrawing member having a toothed and untoothed portion, a rack and pinion connection between the withdrawing member and feeler, a pawl for operating the said member to withdraw the feeler from operative 50 position, and a trip for freeing said member

at intervals that the feeler may have periods of activity and inactivity during weaving with the same supply of filling in the shuttle.

11. In an intermittent feeler mechanism 55 for looms, the combination of a feeler, a feeler withdrawing and holding device, an actuator for the withdrawing and holding device, connections between the feeler and said device for moving the latter into control 60 of its actuator when the feeler is moved forwardly by a working supply of filling in the shuttle on a detecting beat, a feeler stand on which said parts are mounted, and means for freeing the feeler from said device at intervals that the feeler may have periods of activity and inactivity during 65 weaving with the same supply of filling in the shuttle.

12. In a feeler mechanism for looms, the 70 combination of a feeler, a rack and pinion for withdrawing the feeler to a forward inoperative position that it may not engage the filling on detecting beats during its periods of activity, a lock for holding the 75 pinion in feeler withdrawn position, and means for freeing the pinion at intervals that the feeler may have periods of inactivity and periods of activity with the same supply of filling in the shuttle. 80

13. In a feeler mechanism for looms, the combination of a feeler to detect the condition of the filling in the shuttle, means for moving the feeler to a forward position and holding it during its periods of inactivity, a rack and pinion connection between the feeler and said means, and a ratchet and pawl actuated trip for freeing the feeler at intervals. 85

14. In a feeler mechanism for looms, the 90 combination of a feeler to detect the condition of the filling in the shuttle, means for moving the feeler to a forward position and holding it during its periods of inactivity, a rack and pinion connection between the feeler and said means, a bunter adapted 95 to be actuated by a part on the lay, and a trip operated by the bunter to free the feeler at intervals.

In testimony whereof, I have signed my 100 name to this specification.

ALONZO E. RHOADES.
